UNITED STATES PATENT OFFICE.

JAMES L. KLASE, OF CRANFORD, AND ALBERT P. McGRANN AND JOHN J. BACH, OF ELIZABETH, NEW JERSEY.

DESIGN FOR A SMOKER'S TRAY.

60,349.

Specification for Design.

Patented Feb. 7, 1922.

Application filed January 24, 1921. Serial No. 439,698. Term of patent 3½ years.

To all whom it may concern:

Be it known that we, JAMES L. KLASE, ALBERT P. McGRANN, and JOHN J. BACH, citizens of the United States, residing at Cranford, county of Union, and State of New Jersey, Elizabeth, county of Union and State of New Jersey and Elizabeth, county of Union and State of New Jersey, respectively, have invented a new, original, and ornamental Design for a Smoker's Tray, of which the following is a specification, reference being had to the accompanying drawing, forming part thereof.

Figure 1 is a side view of the new and ornamental smoker's tray.

Figure 2 is a top view of a smoker's tray, and

Figure 3 is a front end view of a smoker's tray.

We claim:

The ornamental design for a smoker's tray as shown.

JAS. L. KLASE.

ALBERT P. McGRANN.

JOHN J. BACH.
